UNITED STATES PATENT OFFICE.

AUGUSTUS SEAVER, OF BOSTON, MASSACHUSETTS, ASSIGNOR, BY DIRECT AND MESNE ASSIGNMENTS, TO THE PRISM GLASS GLOBE COMPANY, OF SAME PLACE

DESIGN FOR A MOLD.

SPECIFICATION forming part of Design No. 24,012, dated February 5, 1895.

Application filed December 17, 1894. Serial No. 532,102. Term of patent 14 years.

To all whom it may concern:

Be it known that I, AUGUSTUS SEAVER, of Boston, in the county of Suffolk and State of Massachusetts, have invented and produced 5 a certain new and useful Design for Glass-Molds, of which the following is a specification, reference being had to the accompanying drawing, forming a part thereof.

The leading feature of my design consists 10 in a mold having a conoidal form approximately the shape of a minnie ball, said mold being provided with a serrated surface composed of longitudinal V-shaped grooves that extend lengthwise of the mold and form a 15 series of longitudinal prismatic ribs.

a represents the mold, which is of the general form shown in the drawing, and has a series of longitudinal grooves *b* extending from its smaller end toward its larger end,

said grooves being of varying depth, the depth 20 of each diminishing from its central portion in both directions to its ends.

The grooves form prismatic or V-shaped ribs *b'*, presenting angular edges or apexes extending longitudinally of the mold and 25 tapering gradually from their central to their end portions.

I claim—

The design for a mold, substantially as shown and described.

In testimony whereof I have signed my name to this specification, in the presence of two subscribing witnesses, this 11th day of December, A. D. 1894.

AUGUSTUS SEAVER.
